UNITED STATES PATENT OFFICE.

ALBERT E. KINGSLEY, OF SACCARAPPA, MAINE.

BELT-CLEANER.

SPECIFICATION forming part of Letters Patent No. 299,403, dated May 27, 1884.

Application filed April 7, 1884. (No model.)

To all whom it may concern:

Be it known that I, ALBERT E. KINGSLEY, a citizen of the United States of America, residing at Saccarappa, in the county of Cumberland and State of Maine, have invented certain new and useful Improvements in Belt-Cleaners; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My invention is an improvement in belt-cleaners, the object of the same being to remove from the belt dust, lint, and other materials which would decrease the traction upon the pulleys, the same being intended to be 20 employed in cotton-mills, on spinning, weaving, or carding machines, and upon thrashing-machines, &c.

In the accompanying drawings, forming part of this specification, Figure 1 is a perspective 25 view illustrating my invention applied to a belt, and Fig. 2 is a perspective view illustrating a modification in which the supporting means for the belt-cleaner is adjustable.

A represents cleaners, which are preferably 30 made of sole-leather, brushes, or other equivalent material, which are attached by any suitable means to a bar, B, which bar is secured to suitable stationary portions of machinery, so as to hold the cleaners A against the belt in 35 such a position that they will be inclined across the face of the same. The supports or bars B are bent in any suitable configuration, so that they will hold the cleaners in the desired position.

In cotton-mills and similar places when the 40 machinery is in operation the atmosphere is filled with lint, which adheres to the belts of the machinery and occasions a great loss of power. My invention is designed to obviate this loss of power by removing the particles 45 of lint from the belt, and the cleaners herein-before described are held so as to be in contact with the surfaces of the same, and being at an angle with said belts will remove the lint, causing the same to fall to one side of the 50 belts.

I do not limit myself to the construction shown, as it is evident that my invention can be applied to many different places, and will require a different form of support for almost 55 every class of machinery.

I claim—

1. An improved belt-cleaning device supported in proximity to the belt, and having a flexible portion contacting with said belt and 60 extending diagonally across the same, substantially as set forth.

2. The improved belt-cleaner consisting of a suitable friction-section, A, attached rigidly to a suitable support for holding the cleaner 65 or scraper stationary against the belt, substantially as set forth.

3. In a belt-cleaner, the friction-section A and support B, having one end attached to the section A, substantially as shown. 70

In testimony whereof I affix my signature in presence of two witnesses.

A. E. KINGSLEY.
